(57) **CLAIM**

(**) Term: **14 Years**

(21) Appl. No.: **29/162,380**

The ornamental design for a universal container for chemical transportation, as shown and described.

(22) Filed: **Jun. 14, 2002**

DESCRIPTION

(51) LOC (8) Cl. **09-02**

FIG. 1 is a front elevational view of the universal container for chemical transportation, in accordance with the invention;

(52) U.S. Cl. **D9/531; D9/537**

FIG. 2 is a left side elevational view of our design shown in FIG. 1;

(58) Field of Search D9/499, 516, 517,

FIG. 3 is a side elevational view of our design shown in FIG. 1, rotated approximately 45° in a clockwise direction, as viewed from the top of the container;

D9/530, 531, 537, 538, 541, 549, 551,

FIG. 4 is a rear elevational view of our design shown in FIG. 1;

564, 573–575; 206/527, 815; 215/40, 400,

FIG. 5 is a bottom plan view of our design shown in FIG. 1; and,

382, 384, 398; 220/200, 260, 288, 890

FIG. 6 is a top plan view of our design shown in FIG. 1.
